(57) **CLAIM**

The ornamental design for a utensil rest, as shown and described.

DESCRIPTION

FIG. 1 is a front perspective view of the utensil rest showing our new design;

FIG. 2 is a top plan view thereof;

FIG. 3 is a bottom plan view thereof;

FIG. 4 is a front elevational view thereof, the rear elevational view being an identical mirror image thereof; and,

FIG. 5 is a right side elevational view thereof, the left side elevational view being an identical mirror image thereof.
